by George Francis Myers,
his Attorney.

UNITED STATES PATENT OFFICE

2,090,034

FOUNTAIN PEN

William F. Ellison, Brooklyn, N. Y.

Application January 21, 1937, Serial No. 121,420

1 Claim. (Cl. 120—42)

This invention relates to pens, and particularly to that class thereof known as fountain pens.

It has for its object to produce a fountain pen that can be filled with any liquid, as water for instance, and will write ink.

Another object is to produce a fountain pen having a foolproof connection between the reservoir and the pen point portion so that even if the barrel section be turned upside down no liquid will flow out to soil the fingers; and when the pen point section is replaced there will be a steady flow of the liquid to the pen point when pressed to paper.

Still another object is to produce a fountain pen in which the ink stick, or other soluble ink element is placed directly in the barrel thereof.

The invention also consists in certain other features of construction and in the combination and arrangement of the several parts to be hereinafter described, illustrated in the accompanying drawing as specifically pointed out in the claim.

Figure 1 represents a perspective view of the pen, the particular place or position of the ink stick being shown in dotted lines.

Fig. 2 represents a longitudinal cross section of the pen showing the interior construction and positions of the several parts.

Fig. 3 is a side elevation of the reservoir and appended parts forming a unit, partly in section and particularly pointing out the position of the ink stick.

Fig. 4 is a bottom plan view of Fig. 3.

Fig. 5 is a section along the line 5—5 of Fig. 3.

Fig. 6 is a sectional view of one of the parts contiguous to the tube containing the liquid and fastened thereto.

Fig. 7 is a top plan view of Fig. 6.

Fig. 8 is a longitudinal cross section of the ink stick holder showing the ink stick compartment and the two ducts, or gutters, or slots, one on each side for the full length thereof, and particularly showing that the ink stick compartment does not extend through the said holder from end to end thereof.

Fig. 9 is a bottom plan view of Fig. 8.

Fig. 10 is a cross sectional longitudinal view of the pen holding member which screws into the member shown in Fig. 6.

Fig. 11 is a top plan view of Fig. 10.

Fig. 12 is a side elevation of the feed bar which holds the pen point; and

Fig. 13 is a top plan view of Fig. 12.

Similar numerals of reference indicate similar parts throughout the several views.

The invention is constructed and operated substantially and preferably as follows:

1 is the outer barrel which is securely fastened to the member 3 as at 4; at the further end 5 of the member 3 is fastened the reservoir or water sack 6 as at 7. 3 is provided with two threads on the portion 8; an outer thread 9 which engages with the internal thread 10 on the cap 11 which is placed over the writing end 12 and writing point or pen 13 when the same is not in use, to protect the same from accidental injury; and an internal thread 14 which engages with an external thread 15 on the member 12.

Fastened internally on the narrow end of 3 as at 17 is the ink stick holder 18 having an orifice 19 through its center to near the end thereof where the orifice stops as at 20. The ink stick 21 is held in the said orifice 19. Also there are two slots or gutters 22 extending the full length of the holder, one on each side thereof. The narrow portions 23 and 24 of 12 extend loosely over the ink stick holder, as more particularly shown in Fig. 2. The member 12 has the usual curved-in portion 25 to fit the writing finger as well as the feed bar 26 with its feed slot 27 and pen 13.

When the writer desires to insert a new ink stick he unscrews the cap 31 containing a number of extra ink sticks and selects one thereof; he then unscrews the member 12 from the rest of the pen, and holds the said member 12 in the one hand as a unitary portion, and the other portion of the pen as another unitary portion, as in Fig. 3, in the other hand. If he should turn the last mentioned unitary portion 32, comprising members 1, 6, 3, 18, upside down, no liquid from the sack 6 can flow out thereof; therefore there is no danger of his soiling his fingers. He then holds 32 with its sack downward, as illustrated in Fig. 4, and inserts the selected ink stick in the orifice 19 and brings the said other unitary portion 32, comprising members 12, 13, 26, against 32 and screws the two unitary portions together as at 14, 15; and the pen is ready to write.

As my invention is in some of its aspects generic, I do not limit myself to the particular construction shown and described, but also contemplate the employment of such equivalents as fairly fall within the scope of the claim.

In this connection I may state that although water is specified more particularly for use in my herein invention as it is abundant everywhere, ordinary ink, or any other fluid, may be employed if desired.

Therefore it will be understood that I may make various changes in the form, proportion,

size and detail of the several members shown, and the number and position thereof, without departing from the spirit of the invention.

I claim:

- 5 In a fountain pen, a barrel, a pen section sleeve at the lower end carrying a feeder in the lower portion thereof and an ink stick holder in its upper portion, the said holder comprising a bar

having a slot along the side to the full length thereof, and provided adjacent to its central portion with a perforation which extends, when the pen is held in its writing position, upward from the bottom of the bar but only partway therethrough, and an ink stick mounted in the perforation.

WILLIAM F. ELLISON.
